(57) **CLAIM**

The ornamental design for a cord lock with screw in base feature, as shown and described.

DESCRIPTION

FIG. 1 is a front, right side isometric top view of the cord lock with screw in base feature embodying my new design; FIG. 2 is a top view thereof;

FIG. 3 is a front view thereof, the rear view being a mirror image thereof;

FIG. 4 is a right side view thereof, the left side view being a mirror image thereof;

FIG. 5 is a bottom view thereof; and,

FIG. 6 is a front, left side isometric bottom view thereof.
